CLAIM

The ornamental design for a set of communication equipment, as shown and described.

DESCRIPTION

FIG. 1 is a front elevational view of a set of communication equipment showing my new design with the charging base shown separately for ease of illustration;

FIG. 2 is a rear elevational view of FIG. 1;

FIG. 3 is a left side view of FIG. 1;

FIG. 4 is a right side view of FIG. 1;

FIG. 5 is a top plan view of FIG. 1;

FIG. 6 is a bottom plan view of FIG. 1;

FIG. 7 is a top, front and right side perspective view of FIG. 1;

FIG. 8 is a bottom, rear and right side perspective view of FIG. 1;

FIG. 9 is a top, rear and left side perspective view of FIG. 1;

FIG. 10 is a front elevational view of a set of communication equipment showing the telephone shown separately for ease of illustration;

FIG. 11 is a rear elevational view of FIG. 10;

FIG. 12 is a left side view of FIG. 10;

FIG. 13 is a right side view of FIG. 10;

FIG. 14 is a top plan view of FIG. 10;

FIG. 15 is a bottom plan view of FIG. 10;

FIG. 16 is a top, front and left side perspective view of FIG. 10;

FIG. 17 is a bottom, rear and right side perspective view of FIG. 10;

FIG. 18 is a top, rear and left side perspective view of FIG. 10;

FIG. 19 is a front elevational view of a set of communication equipment;

FIG. 20 is a rear elevational view of FIG. 19;

FIG. 21 is a left side view of FIG. 19;

FIG. 22 is a right side view of FIG. 19;

FIG. 23 is a top plan view of FIG. 19;

FIG. 24 is a bottom plan view of FIG. 19;

FIG. 25 is a top, front and left side perspective view of FIG. 19;

FIG. 26 is a bottom, rear and right side perspective view of FIG. 19; and,

FIG. 27 is a top, rear and left side perspective view of FIG. 19.

(Continued)

The broken lines in the drawings illustrate portions of the set of communication equipment which form no part of the claimed design.
